Patented Mar. 11, 1958

182,288

HOUSE TRAILER

Peter Koller, Hollywood, Calif., assignor to Mid-States Corporation, Union City, Mich., a corporation of Illinois

Application January 7, 1957, Serial No. 44,410

Term of patent 7 years

(Cl. D14—3)

Fig. 1 is a perspective view of a house trailer embodying my new design;

Fig. 2 is a perspective view of a house trailer from opposite side thereof;

Fig. 3 is a rear perspective view thereof.

I claim:

The ornamental design for a house trailer, as shown.
